UNITED STATES PATENT OFFICE.

ROYAL L. BOULTER, OF LOS ANGELES, CALIFORNIA.

ELECTROMAGNETIC TELEGRAPH-KEY.

1,170,796.

Specification of Letters Patent.

Patented Feb. 8, 1916.

Application filed November 13, 1914. Serial No. 871,938.

To all whom it may concern:

Be it known that I, ROYAL L. BOULTER, a citizen of the United States, residing at Los Angeles, county of Los Angeles, and State 5 of California, have invented certain new and useful Improvements in Electromagnetic Telegraph-Keys, of which the following is a specification.

This invention relates to electro-magnetic 10 telegraph keys.

The present invention relates to that class of telegraph keys known as "transmitters" or "vibrators" which employ a vibratory reed subject to the control of an electro-magnet which in turn is controlled by a key. In instruments of this character the key that controls the energization of the electro-magnet need only be pressed to complete the 15 circuit of the electro-magnet when one or 20 more dots are to be formed, as the energization of the electro-magnet sets the reed vibrating and it thereupon forms one or more dots, as desired, thus relieving the operator of the repeated finger and wrist movements 25 necessary with the ordinary telegraph key. Instruments of this character are also provided with a key for the formation of dashes.

Electro-magnetic vibrators or transmitters 30 have the advantage over transmitters or vibrators where the reed is mechanically actuated or released by the movement of the key in that only the slightest touch of the operator is required because the electro-magnet performs the work of setting the 35 reed vibrating.

The present invention preferably employs a vibratory reed of the construction and 40 operation of the mechanically operated vibratory reeds of my Patent, No. 1,110,373, dated September 15, 1914 and my application, Serial No. 854,562, filed August 1, 1914, such reed being set into vibration by the 45 employment of an electro-magnet and armature controlled by novel keys, and a novel arrangement of keys as will appear more fully hereinafter. I wish it understood, however, that I consider my improved keys and novel arrangement thereof to be susceptible 50 of use on an instrument having a vibratory reed of any preferred or desired construction and that they are not limited to use in connection with a vibratory reed of the particular construction hereinafter set forth.

Heretofore transmitters have been generally provided with laterally movable keys. In some instances these keys have been both carried by the same key lever, or vibrator actuator, while in other instances, separate 60 keys have been provided, one for mechanically actuating the reed and the other for forming dashes as, for instance, in the telegraph keys of my Patents Nos. 1,074,831, October 7, 1913; 1,109,818, September 8, 65 1914; 1,110,373, September 15, 1914. In rapid sending where two separate keys are used, it has been found that in the formation of certain letters the tendency is to operate the key so fast that two dashes, as 70 in the letter "M", for instance, are run into one long dash; or a dot, space, and dot, as in the letter "O", for instance, are run too close together with the elimination of the intermediate space and in the case of an 75 "O", an "I" has been formed.

The rocker keys of the present invention overcome and render impossible the running together of short dashes into a long dash or the merging of dots or the omission 80 of spaces between dots. The novel rocker key which is set forth fully hereinafter insures the necessary space between the letters and the combinations which go to make up the letters and enable the operator, regardless of the speed of his sending, to correctly 85 form all letters which conduces to correct receiving at the other end of the line.

My improved rocker keys are duplex and are arranged to complete the circuit at one 90 end or the other of each key according to which end is depressed, but without permitting the making of a contact at one end of the key to lap over on or interfere with the making of a contact at the other end therewith. Combined with these keys are adjusting means and limiting devices, whereby a careful and delicate adjustment will result in the elimination of all idle play and the key 95 will normally stand in neutral, non-contacting position so that the circuit may be closed by depressing either end of the key.

Another feature of the present invention is the relative arrangement of two rocker keys, one for the formation of dots and the 100 other for the formation of dashes and, particularly, an arrangement whereby the operator will use the first and second fingers 105 of both of his hands when sending, for it has been found that in order to afford a certain 110

rhythm to one's sending and to permit each operator to express his individuality in his "Morse," first one hand and then the other should be used and that the same hand should not be used for two successive operations. In the operation of the keys in making the letter "A," which is a dot and a dash, the operator would first make the dot with the left hand, for instance, and then a dash with the right, or vice versa, and in forming this letter he would use both the dot and the dash keys, the dot key being operated by the second finger of one hand and the dash key operated by the forefinger of the other hand. If, for instance, in coming to the end of a word which is being sent, if the last operation was with the right hand, the operator would begin the next word with his left hand whether it started with a dot or a dash. With my improved rocker keys and the relative arrangement of the dot and dash keys, the work of sending is distributed evenly between the two hands of the operator and he thus is enabled to minimize the nervous and muscular strains incident to sending, as also to more or less "play" upon the keys so that sending becomes somewhat of a subconscious operation.

I wish it understood that as I consider myself the first to provide rocker keys constructed and also relatively arranged as hereinbefore explained and hereinafter specifically pointed out in connection with the disclosures of the drawings, I lay claim to this construction and arrangement broadly without limitation to the specific form of vibrator, electro-magnet, or other parts used in connection with the keys to form the complete instrument.

In keys of the vibratory reed type, it is preferable to insure correct sending that the reed immediately come to a state of rest when either its mechanical actuation by a key or electro-magnetic actuation has ceased in order that it may be conditioned to instantly and correctly respond to a subsequent actuation. Heretofore it has been proposed to employ loosely mounted back stops or buffers to arrest the reed on its release. The present invention also contemplates the provision of an improved pivoted back stop whose resistance can be adjusted at will and which will instantly stop every flutter of the vibratory reed when the latter is released, thereby preventing accidental formation of characters and conditioning the vibrator for another operation.

I do not lay claim herein to the construction of the vibratory reed, nor to its manner of pivoting and its spring retraction, nor the improved arrangement of contacts, as these are set forth and claimed in my Patent No. 1,110,373, September 15, 1914, and my application Serial No. 854,562, filed August 1, 1914.

I am aware that changes within the spirit and scope of the inventive features and combinations of the present invention could be resorted to and I do not, therefore, limit myself to details except where particularly specified in the claims.

In the accompanying drawings: Figure 1 is a plan view, dotted lines illustrating the position of the hands when operating the instrument; Figs. 2 and 3, opposite side elevations; Fig. 4, a bottom plan, dotted lines representing the main base; Fig. 5, a partly sectional, partly full line view showing the keys and their bases and insulation; Fig. 6, a detail of the pivotal mounting for the vibratory reed; Fig. 7, a detail of the back stop with certain parts in section; Fig. 8, a detail cross-section through the insulated contact support of the vibratory reed; and Fig. 9, a diagram of the circuit connections.

Preferably, but not necessarily, the instrument is provided with a main base 1 and supplemental base 2, the former being hollow, as shown in Fig. 4, for the accommodation of the conductor cord 3 of the local circuit and conductor cord 4 of the line circuit when disposed beneath the supplemental base 2, and these cords run out loosely through an aperture 5 to their respective plugs or jacks 6 and 7. One terminal of the cord 4 is detachably connected by a clip 8 to the base 1 so that the base 1 which is of metal and is suitably screwed to the supplemental base 2, constitutes a common return for the vibratory reed 9 and the adjustable contact screws 10 and 11 of the dash key 12, as will be evident from the diagram shown in Fig. 9, where dotted lines are shown to indicate that the base 2 constitutes a common return to one branch of the main line 4. A circuit closer 13 is directly mounted on the metallic base 2 to permanently close the main line circuit through the plate 14 which is insulated from base 1 by a sheet of insulation 15 and is connected to the other terminal of the cord 4, such terminal being insulated from the base 2 and being shown at 16. The terminal clips 8 and 16^a are detachable, as are also the terminal clips 17 and 18 of the cord 3, the latter clips being insulated from the metal base 2 and one of them leading to the electro-magnet 19, while the other connects to a metal strip 20, insulated from base 2 and in turn connected by metal strip 21 beneath base 2. Through the ends of the metal strip 21 and through insulating bushings 22 extend the adjustable dot contact screws 23 arranged to coöperate with the dot key 24 which is carried by a metal base 25 mounted upon a sheet of insulating material 26 which is superposed upon the metal plate 14 and is connected by circuit 27 to electro-magnet 19.

I preferably provide the base 2 superposed on and detachably connected to the base 1

and employ the loosely arranged cords 3 and 4 so that these cords may normally lie in the hollow upper face of the base 1, but on removal of the base 2, the said cords may be readily pulled through the opening 5 so that there will be ample opportunity to inspect, adjust or disconnect the connections for the cords 3 and 4.

The adjustable dot contact 28 which operates with the contact 53 on the vibratory reed 9, is insulated from the upper deck 30 at 31 and electrically connected by a metal piece 32 to the plate 14, thereby directly placing the contact 28 in electrical connection with the said plate and through it to the clip 16 to which one terminal of the cord 4 of the main line is connected. The deck 30 is supported by pillars 33, two of which extend considerably thereabove, as shown at 34 and are connected by a yoke 35.

The vibratory reed 9 which is substantially the same construction as that disclosed in my co-pending application, Serial No. 854,562, is of resilient material throughout and is connected to plates 37 preferably by riveting, and these plates have a trunnion 38 whose upper tip is journaled in a screw 39, while its lower end or point is received in a concavity in the deck 30, whereby the vibratory reed is pivotally mounted. To an extension 40 of the plates 37 is suitably secured a vertically disposed armature 41 which is arranged in line with the poles of magnet 19. The vibratory reed 9 is directly and positively spring-retracted by a compression coil spring 42 which engages the extension 40, the latter being provided with an aperture 43 to receive one tip of said spring, while the other tip thereof is entered in the hollow end of an adjusting screw 44 which is threaded through a bracket carried by one of the pillars 34. By this means, the retracting tension of the spring on the vibratory reed 9 may be changed at will. It will be seen, therefore, that the vibratory reed 9 is normally retracted to the position shown in Fig. 1 solely by the action of said spring 42.

Secured between the plates 37 is a tapping spring 45 which is resilient throughout its length and projects freely from between said plates and lies in an open portion 46 of the reed 9. The free end of this tapping spring is provided with a stop or arrester 47 which overlaps the reed and is adapted to bear against it, due to the resiliency of said spring 45. Spring 45 is provided with a contact 48 adapted to coöperate with the tip 49 of an adjustable contact screw 50 for the purpose of automatically forming a plurality of dots, when the armature is attracted by the electro-magnet 19. The screw 50 is carried by a rod or tube 51 which is slidably mounted in a block 52 so that the said rod or tube can be moved lengthwise in re-

lation to the length of the reed 9. Consequently, a very fine relative adjustment of the contacts 48 and 49 can be effected. The block 52 carries a contact 53 adapted to engage the contact 28 when the vibrator is swung by the energization of the electro-magnet 19. A suitable nut may be provided on the block 52 and the contact 53 may project from this block. If this nut or head is provided, it affords means for turning the parts to effect as fine an adjustment of the contacts as desired.

Referring to Fig. 8, the plates 37 are provided with apertures in which is a bushing 54 of insulating material through which passes the screw-threaded stem 55 which has a head 56 provided with a hole of approximately the same size as the hole in the block 52 which receives a rod or tube 51, and the rod or tube 51 passes through the said hole. Insulating washers 57 and a nut 58 on the screw 55, as also a metallic washer 59, afford means for clamping the parts together so that the block 52 and rod or tube 51 will be firmly secured, in any suitable position, in relation to the reed. It will be observed, however, that the block 52 is pivotally mounted on the part 56 and, consequently, the contacts can be raised or lowered on releasing the nut and on again clamping the nut, they will be held in adjusted position, whereby up and down adjustment, in addition to the longitudinal adjustment heretofore referred to, is obtainable. A very fine adjustment of the contact mechanism is, therefore, insured.

When the reed 9 is moved by the energization of the electro-magnet 19, the contacts 53 and 28 are brought together. If but a single dot is to be made, the key 24 having been released by the operator, the electro-magnet 19 will be at once deenergized and only one dot results, but if the operator holds the key 24 depressed, the arrest of the reed 9 by the engagement of contacts 53 and 28 causes the reed to vibrate, whereupon it repeatedly separates from and strikes the stop or arrester 47 by alternate movements and thus exercises a tapping movement on said arrester 47, which is in turn communicated to the flexible member 45, resulting in the contact 48 alternately repeatedly striking and disengaging from the contact 49, whereupon the circuit of the main line circuit 4 is repeatedly opened and closed, thus automatically forming a succession of dots. During this vibration of the reed 9, the contacts 53 and 28 remain engaged. Immediately the key 24 is released, the local circuit 3 is broken and the magnet 19 becomes deenergized, whereupon the reed is retracted by the action of the coil spring 42. The reed is provided with an elongated slot 60 to permit adjustment of the bob or weight 61. By shifting the bob or weight 61 to

different positions, the rapidity of vibration of the reed may be increased or diminished.

To instantly stop all fluttering or vibration of the reed 9, immediately the electro-magnet is deenergized, I provide a back stop 62 which is pivotally mounted in pillars 63 and has a bar of sufficient length to receive the impact of the bob 61 wherever the latter may be positioned. The back stop 62 is provided with a depending part 64 which has a lateral arm 65 located below the deck 30 and carrying an adjustable weight 66. The amplitude of movement of the depending part 64 may be controlled, as desired, by 15 adjustable abutments 67 carried by the under face of deck 30. By adjusting the play of the back stop and moving the weight 66 to the proper position, the cushioning action of the back stop may be regulated so 20 that the reed will immediately come to rest when the magnet is deenergized.

The keys 12 and 24 are constructed and mounted in the same manner and their tension devices and stops are of the same construction and coöperate with them in the same fashion. A description of one of these keys and its allied parts will, therefore, alone be given. The key is provided at opposite ends with finger pieces 68 and 69 and 25 with contacts 70 and 71. The contact 70 of the key 12 is adapted to strike the contact 10 and the contact 71 to strike the contact 11. The corresponding contacts of the key 24 strike the contacts 23. Each key is pivoted intermediate its ends. In the case of the key 24, a yoke 72 is secured to the base 25 and with the key 12, a similar yoke 73 is secured to the plate 14. Pivoted trunnions 74 are slidably connected to the yoke by clamping 30 screws 75, their points entering concavities 76 in opposite sides of the key. Each key is flanked by tension and stop bars 77 which are loosely mounted on the trunnion 74. Carried by these bars are tension screws 78 35 which receive the tip of a coil spring 79 whose other end enters an aperture 80 in the base plate below. Threaded through the opposite end of the bar is a stop screw 81 which is adapted to strike the base plate to limit 40 the swing imparted to the bar by the spring aforesaid. This screw passes loosely through a stop 82 which overlies the key. A nut 83 on the screw clamps the stop against the top of the bar and also serves as a set 45 nut for the screw. The screw, therefore, has the double function of holding the stop and limiting the swing of the bar. The arrangement of the bars is such that the respective stops 82 are arranged on opposite 50 sides of the pivotal point of the key and the springs are arranged transversely opposite the said stops. In consequence of this construction, the key is normally held by the 55 springs and the screws in an intermediate or 60 neutral position and the circuit is broken. 65

When either key button or finger piece is depressed, the key will rock on its trunnions and complete the circuit through the contacts, but immediately it is released, it will resume its neutral position. It will be understood that the same circuit is completed by the key 12, regardless of which end thereof is depressed, as will be apparent from Fig. 9. Similarly, the circuit of the electro-magnet will be completed, regardless of 70 whichever end of the key 24 is depressed. It will be observed that the key 12 is used for the formation of dashes and the key 24 for the making of dots.

When the instrument is used, it faces the 83 operator in the position shown in Fig. 1 and the operator employs both hands in manipulating the keys 12 and 24, as shown by dotted lines in said Fig. 1, the forefinger of the operator's hands being adapted to coöperate 85 with the buttons at the opposite ends of the key lever 12 and the second fingers with the buttons at the ends of key levers 24. As each key is mounted intermediate its ends, it is impossible for the finger of one hand 90 to make a dot or dash so close to the dot or dash formed by the finger of the other hand that there will be any merging of dots, elimination of spaces, or merging of short dashes. It will be observed that the key lever 12 is 95 shorter than key lever 24 to enable the fingers of the operator to naturally assume their positions on the key buttons while the arms of the operator are in natural position. Were the buttons of the two keys spaced the 100 same distance apart, the arms of the operator would be in an unnatural position and sending would be difficult. In operating the instrument, the same hand should not be used for two successive operations. For instance, in making "A," which is a dot and a dash, the dot is made by using the second finger of the left hand, let it be assumed, and then the dash by depressing the right hand 105 end of lever 12 by the forefinger of the right hand, or vice versa. In coming to the end 110 of a word, if the last operation was with the right hand, the next operation would be with the left hand, regardless of whether a dot or a dash is to be formed.

With an arrangement of keys as set forth, the operation of sending is evenly distributed between the fingers of the two hands and the strain on the nerves and muscles is minimized, thereby very greatly 115 lessening the occurrence of telegrapher's paralysis. After a little experience, the operator naturally sends with both hands and, in effect, plays on the keys. This enables perfection in sending with both 120 hands so that if one of an operator's hands has become disabled, he is not thereby incapacitated for service. However, as the depression of either end of key 12 will form 125 a dash and, similarly, the depression of 130

either end of key 24, a dot, the operator can send by using but one hand, in which event, the instrument is turned to face the operator at right angles to the position 5 shown in Fig. 1.

The electro-magnet 19 is carried by a yoke 84 which rises from parallel guide rods 85 slidable in guides 86. One of the 10 guide rods is provided with screw-threads 87 on which are adjusting nuts 88 which enable the magnet to be adjusted one way or the other by their coöperation with one of the guides aforesaid; thus enabling the poles of the magnet to be brought as close 15 or as far away from the armature as desired, according to the strength of the current and existing conditions.

It will be observed that in my invention the electro-magnet is in the normally open 20 and deenergized circuit 3 which includes the dot key 24 and hence is distinguished from those electro-magnetic transmitters heretofore known which either embody an electro-magnet in the normally energized 25 circuit, or, where the vibrator is mechanically held or controlled by the operating key. In my invention, the current for the electro-magnet is only used when the dot key is depressed, which results in very 30 slight consumption of current, and because the circuit is local, a light current can be used to afford a very strong magnetic attraction on the armature of the vibrator, is not subject to main line troubles, etc. 35 Furthermore, in my invention, the operation of the vibrator is a positive one when the dot key is depressed, because the electro-magnet positively attracts the armature and positively moves the vibrator to close the 40 circuit and start the vibrator vibrating for the formation of dots. In earlier electro-magnetic vibrators, a spring or springy part of the reed has been employed for the initial movement of the vibrator or for all 45 of its movements, instead of being a direct and positive electro-magnetic action, as with my invention.

Having thus described my invention, what I claim as new and desire to secure 50 by Letters Patent, is:

1. In an electro-magnetic telegraph key, the combination of a pivoted and bodily movable inherently vibrative reed, a spring for normally retracting said reed, electrical 55 contacts controlled by the reed, an electro-magnet for actuating the reed, and a key controlling the electro-magnet.

2. In an electro-magnetic telegraph key, the combination of a pivoted and bodily 60 movable inherently vibrative reed, a spring for normally retracting said reed, normally open electrical contacts which are closed and opened when the reed is actuated, an electro-magnet for actuating the reed, and a key controlling the electro-magnet.

3. In an electro-magnetic telegraph key, a vibratory reed, electrical contacts controlled thereby, an electro-magnet for actuating the reed, a normally open key, and a local circuit including the magnet and 70 the key, whereby said magnet is normally deenergized, said reed being pivoted, and a spring coöperating with the reed adapted to retract it so that it is normally conditioned for actuation by the electro-magnet. 75

4. In a telegraph key, the combination with a vibrator, of a pivoted, rocking back stop coöperating with the vibrator, and means for regulating at will the resistance afforded by said back stop. 80

5. In a telegraph key, the combination with a vibrator, of a pivoted, rocking back stop coöperating with the vibrator, and means for regulating the resistance afforded by said back stop consisting of a laterally 85 extending arm and a bob or weight adjustably mounted on said arm and adapted to be held at different positions thereon.

6. In a telegraph key, a rockably mounted key lever, electric circuit controlling contacts adapted to coöperate with the lever on opposite sides of its mounting, and means for normally maintaining the key lever in neutral and "open" position in relation to both contacts. 90

7. In a telegraph key, a rockably mounted key lever, contacts adapted to coöperate with the lever on opposite sides of its mounting, independently adjustable springs coöperating with the key lever on opposite sides of 100 its fulcrum, and stops coöperating with the key on opposite sides of its fulcrum, whereby the key may be tensioned as desired and normally maintained in neutral or non-contacting position. 105

8. In a telegraph key, a rockably mounted key lever, contacts adapted to coöperate with the lever on opposite sides of its mounting, rockable bars, springs coöperating with one end part of each of the bars, and stops 110 coöperating with the opposite ends of the bars and also with the key lever on opposite sides of its fulcrum, whereby one bar and its spring and stop controls the movement of the key lever in one direction and the 115 other bar and its spring and stop controls the movement of the key lever in the opposite direction, said bars, springs and stops being adapted to maintain the key lever in neutral and noncontacting position. 120

9. In an electro-magnetic telegraph key, the combination with a vibratory reed and electrical contacts controlled thereby, of an electro-magnet controlling the vibratory reed, contacts respectively in circuit with the 125 electro-magnet, and a duplex rocker key adapted to remain normally in neutral position or non-contacting relation to the aforesaid contacts and for movement to engage one or the other of said contacts at a 130

given time, whereby said electro-magnet may be controlled by rocking the duplex key in one direction or the other.

10. In an electro-magnetic telegraph key, 5 the combination with a vibratory reed and electrical contacts controlled thereby, of an electro-magnet controlling the vibratory reed, contacts respectively in circuit with the electro-magnet, a duplex rocker key adapted 10 to remain normally in neutral position or non-contacting relation to the aforesaid contacts and for movement to engage one or the other of said contacts at a given time, whereby said electro-magnet may be controlled 15 by rocking the duplex key in one direction or the other, a line circuit adapted to be opened and closed by said vibratory reed, and a duplex rocking key in the line circuit and adapted for forming dashes, said 20 key embodying contacts adapted to be individually engaged according as the key is rocked in one direction or the other, said dash key having means for maintaining it normally in neutral and non-contacting 25 position.
11. In a telegraph key, the combination with dot-forming means and a line circuit subject thereto, of a duplex dot key controlling the dot-forming means, and a duplex dash key for sending dashes over the line circuit, said keys being each adapted 30 for use by either or both of the hands of the operator.
12. In a telegraph key, the combination 35 with dot-forming means and a line circuit

subject thereto, of a duplex rocker dot key, contacts for each end portion thereof controlling the dot-forming means, a duplex rocker dash key, and contacts for each end portion thereof for sending dashes over the 40 line circuit, said keys being arranged in juxtaposition and each adapted for use by either or both of the hands of the operator.

13. In an electro-magnetic telegraph key, the combination with a vibratory reed, of 45 an electro-magnet controlling said reed, dot-forming contacts controlled by the reed, a line circuit, independent duplex dot and dash keys having means for maintaining them in neutral non-contacting position, 50 contacts for the respective keys, whereby the circuit may be controlled on the operation of either part of either duplex key, the aforesaid duplex dot and dash keys being arranged in juxtaposition so that they are 55 adapted for operation by both hands of the operator.

14. A telegraph key comprising duplex normally non-contacting dot-sending and dash-sending instrumentalities arranged in 60 juxtaposition to adapt them for conjoint operation by either one hand or both hands of the operator.

In testimony whereof, I hereunto affix my signature in presence of two witnesses.

ROYAL L. BOULTER.
